UNITED STATES PATENT OFFICE.

JULIUS EWIG, OF SPRINGFIELD, MASSACHUSETTS.

GAME DEVICE.

Application filed January 2, 1923. Serial No. 610,348.

To all whom it may concern:

Be it known that JULIUS EWIG, citizen of the United States of America, residing at 94 Rittenhouse Ter., Springfield, in the county of Hampden and State of Massachusetts, has invented certain new and useful Improvements in Game Devices, of which the following is a specification.

This invention relates to improvements in game devices and its leading object is to provide a mechanism for playing various card games, such as are now generally played with the popular deck of fifty-two cards consisting of four groups or suits of thirteen individual cards, commonly designated, clubs, diamonds, hearts and spades. The mechanism involves means whereby various games now played with a standard deck of cards, or with any abbreviation or enlargement of the standard deck, can be played, and any play action which may be possible in any other similar card game may be reproduced with my improved game device or apparatus.

With the above and other objects in view the invention consists in certain new and useful constructions, combinations and arrangements of parts, clearly described in the following specification and fully illustrated in the accompanying drawings, in which:—

Fig. 1 is a plan view of a preferred form of the invention.

Fig. 1^a is a detail of a modified view of a pin.

Fig. 2 is a vertical sectional view of the invention.

Fig. 3 is a plan view of a modified form.

Fig. 4 is a vertical sectional view thereof.

Fig. 5 is a plan view of a modified form showing a table provided with four suit symbols.

Fig. 6 is a similar view of another form showing a table carrying twelve suit symbols, or three sets thereof.

Fig. 7 is a plan view of a modified form of a spinner provided with four suit symbols.

Fig. 8 is a similar view of another modified form showing a table provided with twelve suit symbols.

Referring to the accompanying drawings illustrating the practical embodiment of my invention 5 designates a stationary base, which is provided with a central upstanding pivot 6, secured thereto by means of the screws or the like 7. This pivot or pointed

bearing projects above the bottom 8 of the well 9 formed in said base and is engaged by the bearing 10 carried by the circular member 11, which is shaped to freely rotate in the well 9 when the holding pin 12 is in the position shown in Fig. 1. This pin is provided with a flat face 12^a which normally clears the periphery of the member 11, when the lateral arm 12^b of said pin is in the position shown in Fig. 1. By partially rotating the pin so that its round face 12^c will be brought into binding engagement with the periphery of the spinner 11, this spinner may be held against rotative member 65 on the base.

The spinner 11 is formed with a series of radially spaced sockets 13 in which pins 14 may be detachably inserted. Fifty-two of such sockets are arranged in evenly spaced relation in a circle around the circular wall 11^a of said spinner. This wall forms, with the bottom 11^b, of said spinner, a well in which the inner spinner 15 is arranged to rotate. This inner spinner is preferably formed of metal and is provided with a series of small recesses or pockets 16, which are arranged in a circle near the periphery thereof. The central portion of the inner spinner is dished or drawn upwardly to provide a dome-like surface, while the outer marginal edge portion thereof is disposed at a slight angle, outwardly of the circular row of recesses or pockets, so that the selector ball 17 will roll into one of the recesses 80 or pockets when the inner spinner comes to a spot, after having been rotated by a manually spinner action.

In Fig. 1^a a modified arrangement of the pins 14 is shown. Referring to Fig. 1^a 14^a 95 describes a pin having a ball 14^b on its lower end which is normally retained in a split socket 14^c carried by the pin 14^d. When it is desired to move the pin 14^a to an inactive position it is merely swung horizontally in the socket 14^c. This arrangement does not require the removal of the ball and socket pin construction.

A single selector ball is employed but the number of the recesses or pockets equals 105 to the number of sockets 13 formed in the outer member or spinner 11. The spinner 15 rotates upon the upstanding pin 18 secured at its lower end to the central portion of the spinner 11, as shown in Fig. 2 in cross section. The inner spinner has a hub 19 which is provided with a screw 20 and the

handle 21 is threaded on this screw. A selector arrow 22 is mounted at its inner end by means of the bearing 22^a on the hub 19 to rotate, at the will or desire of the player, 5 over the face of the inner spinner 15. In order to lock this arrow against rotative movement relative to the inner spinner the handle 21 may be threaded snugly against the bearing eye 22^a of said arrow 22, and 10 held in either its normal loose position or in its holding position by means of the set screw 23, which is threaded into the handle against the upper end of the connecting screw 20.

15 The arrow 22 may be used with or without the ball. By turning the handle the inner spinner may be rapidly rotated to cause the selector ball or the arrow to set up a relative motion on the inner spinner. The 20 final position assumed by the selector ball or arrow will determine the character of the play.

The outer marginal edge portion of the inner spinner is provided with a series of 25 card indexes 24, representing the fifty-two cards of a standard deck of playing cards, and arranged in mixed formation in a circular row surrounding the circular row of recesses or pockets 24^a. The value of the 30 play is determined by the card value thus given to the individual pocket or recess into which the ball enters, or which is indicated by the point of the selector arrow when it comes to a stop or by the pin nearest to one 35 of the indexes when the spinner stops. In making an individual play the player first locates a pin in one of the numbered pockets of the outer spinner. The outer spinner 11 may also be rotated by finger manipulation 40 of the upper horizontal surface of its wall, so that a great relative variation is possible.

The use of the pins 14 and 14^a permit of 45 a selection independent of that obtained by the action of the ball 17 in the recesses 16, this independent selective action being desired in various kinds of special games and is capable of being used without employing the ball 17.

Various games in addition to the games 50 usually played with standard playing cards may be played by the use of my improved game device, and any number of players, within the mechanical limits of the game device, may participate in any of the games 55 played, depending, of course upon the governing rules of the game being played. Each player selecting one or more pins to indicate his or her play, depending on the rules governing. In some games the pins 60 would not be used.

In Figs. 3 and 4 I show a modified form 65 of the invention comprising a base 30 on which the outer spinner 31 works, on this spinner 31 the inner spinner 32 works, both spinners being mounted for rotation upon

the upstanding shaft 33, the lower end of which is fixed to the base 30.

The outer spinner is provided with a series of divisions which represents the unit cards of a single suit, any suit, of a standard four suit deck of cards. The inner spinner is provided with a series of divisions which carry the symbols or figure designs of these four suits, namely, clubs, hearts, spades and diamonds. The units of the suits being designated by the reference 70 34 and the color or kind of the suit being designated by the reference 35. The symbols of the suits are preferably arranged 75 with the red and black colors alternating, 80 as diamond, or red, club or black, heart, or red and spade, or black.

By imparting rotative movement to the spinner discs any of the various plays possible in a standard card game can be effected 85 by the use of the device shown in the Figs. 3 and 4.

In Fig. 5 I show a modified form of the invention wherein a spinner disc 40 is arranged to rotate around the axis 41, by 90 means of a finger turned knob 42, carried by the disc. This disc is provided with a series of ball pockets or recesses 43, located in its marginal edge portion, and arranged in line 95 or adjacent to a circular row of numbers or value designations 44, beginning from 1 and running to 10, and thence including the letters J, Q and K, representing the jack, queen and king, of a standard card deck, while the numbers represent the other cards of the 100 suits. The spinner disc rotates within a member or table 45, which is shown to be divided into four quarters, in each one of which a card or suit character or symbol 46 is located, representing, respectively, the 105 suits of diamonds, hearts, clubs and spades. A ball 47 cooperates with the spinner disc and is adapted to roll into one of the pockets of said disc when the disc comes to a stop. Holes 48 are formed in the table 45 to permit 110 one or more players to designate the suit being played. When the ball comes to a stop with the spinner disc the suit symbol in the nearest sector of the circular table will be designated as the card being played. For 115 instance, if the ball enters the pocket designated "8" with this pocket in line with the sector in which the diamond symbol is located, then an eight of diamonds will be indicated.

In Fig. 6 I show a similar arrangement, except that the table 45^a is provided with a larger number of suit symbols.

In Fig. 7 I show a reversed arrangement, wherein the table 50 carries the suit value 125 numbers and letters, separated from each other by division lines, and the spinner 51 is divided into quarters and the suit symbols are arranged in these quarters. In each quarter of the spinner three pockets for the 130

selecting ball are arranged, and a pin hole is preferably located in line with each suit character or number.

In Fig. 8 the spinner 51^a is shown to be provided with a larger series of suit symbols, 5 three sets being shown, arranged in alternative order. A pocket 51^b is located in line with each symbol. The table 50^a is provided with 10 numbers and three letters, representing the member cards of each suit. 10

By rotating the spinner of either form shown on sheet 3 of the drawings, it is possible to play any card value used in any of the ordinary card games, employing the 15 standard card deck of fifty-two cards. By using a series of selector pins a number of players may participate in the game being played.

Having described my invention I claim:—

20 1. A game device consisting of a member provided with a series of selector positions, a spinner rotatively mounted in the member and carrying a series of individual card value indexes representative of a complete 25 standard card deck of fifty-two cards, and means cooperating with the spinner whereby various plays may be produced by rotating the spinner.

2. A game device consisting of a member 30 provided with a series of selector positions, means of selecting either one or a number of said positions, a spinner carrying a series of card indexes representing a standard card 35 deck of fifty-two cards and provided with play locations in line with said indexes, the

selector positions being equal in number to the number of the indexes, and a selector cooperating with the spinner whereby any one of the indexes may be selected in a spinning of the spinner. 40

3. A game device consisting of a stationary member, an outer spinner mounted for rotation thereon, said outer spinner carrying a series of position indicators, an inner spinner mounted for rotation within the 45 outer spinner and carrying a series of card indexes comprising the whole of a standard card deck of fifty-two cards, the inner spinner being provided with position locations in line with the card indexes, and a selector 50 arranged for relative motion on the inner spinner and adapted to register with any one of the position locations thereof.

4. A game apparatus comprising a stationary member, an outer spinning member 55 adapted to rotate on the stationary member, means for locking said outer member against rotating said outer member against rotation at will, an inner spinning member arranged to spin within the outer spinning member, 60 one of said spinning members being provided with a series of selective positions circumferentially spaced from each other and the other spinning member being provided with a series of characters representing 65 suites of a standard deck of fifty-two cards and the successively numbered values of each suite.

Signed by me at Springfield, Mass.
JULIUS EWIG.
